UNITED STATES PATENT OFFICE.

JOSEPH ENIS, OF RIFTON, NEW YORK, ASSIGNOR TO BIGELOW HARTFORD CARPET COMPANY, A CORPORATION OF MASSACHUSETTS.

DESIGN FOR A RUG.

49,084.

Specification for Design.

Patented May 23, 1916.

Application filed March 29, 1916. Serial No. 87,636. Term of patent 3½ years.

To all whom it may concern:

Be it known that I, JOSEPH ENIS, a citizen of the United States, residing in Rifton, in the county of Ulster and State of New York, have invented a new, original, and ornamental Design for a Rug of Carpet Sizes, of which the following is a specification, reference being had to the accompanying drawing, forming part thereof.

The drawing illustrates a portion of a rug showing my new design.

I claim:

The ornamental design for a rug, substantially as shown.

JOSEPH ENIS.
